EYE PROTECTOR

Nelson M. Baker, Southbridge, Mass., assignor to
American Optical Company, Southbridge,
Mass., a voluntary association of Massachusetts

Original application October 18, 1927, Serial No.
226,900, now Patent No. 1,807,681, dated June 2,
1931. Divided and this application March 22,
1930. Serial No. 438,204

3 Claims. (Cl. 2—14)

This invention relates to eye protectors for goggles, and has particular reference to a goggle adapted for the use of aviators. This application forms a division of my application Serial Number 5 226,900, filed October 18, 1927, patented June 2, 1931, #1,807,681.

The principal object of this invention is to provide means whereby the amount of ventilation in an eye protector may be varied to suit the 10 condition under which said eye protector is used.

Another object of this invention is to provide an eye protector particularly adapted for aviation and other high speed occupations, by having ventilating means variable according to the velocity 15 of the external air.

Another object of the invention is to provide an improved means for fitting such a device to the face of the wearer, whereby the air or wind from the outside will not enter the eyecup, except 20 as provided for ventilation.

Another object of this invention is to provide simple and economical means of accomplishing said reduction or increase of the ventilating air supply to an eye protector.

25 Other objects and advantages will become apparent from the following description taken in connection with the accompanying drawing, and it will be understood that many changes may be made in the details of construction and arrangement of parts without departing from the spirit 30 of the invention, as expressed in the accompanying claims. I, therefore, do not wish to be limited to the exact details shown and described, as the preferred forms only have been shown by way of 35 illustration.

Referring to the drawing, Fig. I is a front view of the device in place on the face of the wearer.

Fig. II is a top view of Fig. I.

Fig. III is a cross section on line III—III of 40 Fig. II.

Fig. IV is a cross section on line IV—IV of Fig. III.

Fig. V is an enlarged sectional view of the 45 ventilation opening shown in Fig. III.

Fig. VI is a cross section on line VI—VI of Fig. V.

Fig. VII is a partial cross section on line 50 VII—VIII of Fig. III.

Fig. VIII is a view similar to Fig. V, showing one end of the air chamber closed.

Eye protectors for aviators, automobilists, and others engaged in high speed occupations are usually ventilated by a suction device of some nature, which is dependent upon the velocity of 55 the wind and the speed of the machine for its

operation. Usually, the wind thus created, is allowed to pass through a specially designed chamber and to draw, as it goes, the warm air from the interior of the eye protector. It will readily be seen from this operation that a device 60 which is quite efficient at slow speed by giving sufficient ventilation, will invariably give too much at a higher rate of speed. The contrary is, of course, true, and if the ventilation is made for a high rate of speed such as is usual in combat 65 planes, it will be too restricted for use in ordinary transport work. It is the prime object of my invention therefore, to provide a ventilating device for these eye protectors which will vary the flow of air to the interior of the eye 70 protector, according to the speed at which the user is traveling, or the velocity of the wind across his head.

Referring to the drawing wherein similar characters of reference denote corresponding 75 parts throughout the several views, the improved goggle comprises a pair of eyecups 1 carrying lenses 2. The eyecup 1 comprises an outer rim or ring 3, having a flanged lens seat 4 and an inner ring or rim 5 between which is held the 80 flange 6 of the resilient face contacting member 7. The face contacting ring 7 has the enlarged portion 8 for engagement with the face and this ring is made preferably of soft rubber. The eyecups 1 are secured one to the other, by the 85 bridge 9. In Fig. I it will be noticed that on the nasal side of the eyecup there is a projection 12 of the resilient ring 7, fitting into the nasal socket. It has been found from experience that ordinarily, goggles of this type do not fit snugly 90 into the nasal socket or canthus; hence, an open space is left which allows the wind to be driven in through the opening in the eyecup. This defect is overcome by enlarging the enlarged portion 8 to fit into the nasal canthus, as has been 95 described. This is an important feature of the present invention. It will be understood that the projections 12, being of tough rubber, are very resilient, and fit themselves naturally and easily 100 to noses of various sizes and to contours of the nasal canthus of various shapes. The eyecups are ventilated through the openings 29 in the rim 3 and 30 in the rim 5 on one side of the eyecup, and by the tubular lug 31 having a tubular sleeve 32 with a plurality of openings 33, aligning with the opening 34 in the rim 3, see Fig. V. The sleeve 32 in Fig. V is open at both ends. In Fig. VIII the sleeve is closed at one end, as shown at 35. The tubular lug 31 is fitted 110

with the pin 36 which fits into an elongated slot 37 in the sleeve 32.

By rotating the sleeve 32 in the lug 31, either one or more of the openings 33 may be thrown into line with the opening 34 in the rim 3, and in this way, the amount of ventilation may be regulated. The pin 36 holds the sleeve 32 in the extreme open and closed positions, and against removal therefrom. The construction and operation are best shown in Figs. V and VI. A suction is caused by the air rushing through the tube of the lug 31. This draws the air in through the openings 29 and 30 in the rims 3 and 5. In Fig. VIII the air, instead of rushing through the tubular lug 31, rushes over the top, and past the orifice of the member 32. From the above description it will be seen that when the speed of the plane is reduced, or the velocity of the wind drops, the suction in the ventilation means will correspondingly grow less. The sleeve 32 in the lug 31 may thereupon be rotated until the desired amount of ventilation is obtained.

From the foregoing, it will be readily seen that I have provided extremely simple and novel means of accomplishing the objects of this invention, particularly in providing means of reducing the suction in an eye protector when increased speed or greater wind velocity necessitates said reduction for the comfort of the wearer.

Having described my invention, I claim:

1. In an ophthalmic mounting, an eyecup hav-

ing orifices on opposite sides thereof, a sleeve bearing adjacent one of the orifices, and a rotatable sleeve in the sleeve bearing and having an orifice aligned with the orifice in the eyecup whereby by rotating the sleeve in the sleeve-bearing the orifice in the sleeve may be brought to open into the orifice in the eyecup or the orifice in the eyecup may be closed by the non-perforate portions of the sleeve.

2. In an ophthalmic mounting, an eyecup having orifices on opposite sides thereof, a sleeve bearing adjacent one of the orifices, and a rotatable sleeve in the sleeve bearing and having a plurality of orifices aligned with the orifice in the eyecup whereby by rotating the sleeve in the sleeve-bearing a selected number of the orifices in the sleeve may be brought to open into the orifice in the eyecup or the orifice in the eyecup may be closed by the non-perforate portion of the sleeve.

3. In an ophthalmic mounting, an eyecup having orifices on opposite sides thereof, bearing means adjacent one of the orifices, movable valve means in the bearing means and having an orifice aligned with the orifice in the eyecup whereby by moving the valve means in the bearing means the orifice in the valve means may be brought to open into the orifice in the eyecup or the orifice in the eyecup may be closed by the non-perforate portion of the valve means.
